COVER FOR SPOKED CYCLE WHEEL

Robert T. Powell, 1682 Grasscreek Drive,
San Dimas, Calif. 91773

Filed Feb. 13, 1970, Ser. No. 21,431

Term of patent 7 years

Int. Cl. D12—14

U.S. Cl. D14—30

FIG. 1 is a perspective view of the cover for spoked cycle wheel of this invention;

FIG. 2 is an edge elevational view;

FIG. 3 is a front elevational view;

FIG. 4 is a back elevational view; and

FIG. 5 is a detail sectional view on the line 5—5 of FIG. 3.

I claim:

The ornamental design for a cover for spoked cycle wheel, substantially as shown.
